UNITED STATES PATENT OFFICE.

RICHARD EISENMANN, OF CHICAGO, ILLINOIS.

TIRE-SUPPORTING RECEPTACLE.

1,091,818.

Specification of Letters Patent. Patented Mar. 31, 1914.

Application filed May 8, 1913. Serial No. 766,348.

To all whom it may concern:

Be it known that I, RICHARD EISENMANN, a citizen of the United States, residing at Chicago, in the county of Cook and State of Illinois, have invented certain new and useful Improvements in Tire-Supporting Receptacles, of which the following is a specification.

My invention relates to receptacles, and particularly to receptacles adapted to be placed within and secured to the spare tires usually carried on automobiles. A receptacle of this sort is subjected necessarily to considerable vibration and often to some hard usage, and therefore, if a door or cover of ordinary construction is used, it will soon become loose or warped or otherwise injured so that the receptacle is not dust and waterproof.

One of the principal objects of my invention is to provide, in a receptacle of this character, a door which is so constructed that when shut it provides a tight fitting closure for the receptacle that will not gap or rattle loose with the vibration of the car and that will automatically take up any looseness and wear.

A further object of the invention is to provide a simple and convenient means for locking a door of this sort in its closed position.

A further object of the invention is to provide certain novel means for securing the receptacle within the tire.

The preferred embodiment of my invention is shown in the accompanying drawings, in which similar characters of reference designate corresponding parts, and in which—

Figure 1 is a side elevation of the receptacle. Fig. 2 is a section taken on line 2—2 of Fig. 1, looking in the direction indicated by the arrows. Fig. 3 is a view in elevation illustrating the position of the resilient locking member when it is in an unlocked position, showing parts of the body in section. Fig. 4 is a view similar to that of Fig. 3 showing the locking member in locked position. Fig. 5 is a plan view of the structure shown in Figs. 3 and 4. Fig. 6 is an enlarged sectional view illustrating the manner of securing the tire to the outer periphery of the receptacle. Fig. 7 is a view, in perspective, of the tire securing device shown in Fig. 6 removed from the receptacle. Fig. 8 is a view, in perspective, of

one of the buckles. Fig. 9 is a sectional view of the buckle taken on line 9—9 of Fig. 7, and Fig. 10 is a perspective view of an angular bracing element.

Referring to the drawings, 25 designates the body of the receptacle which is cylindrical in form and may be secured in a vertical position inside the extra tire usually carried on automobiles, when the extra tire referred to is carried on the mud guard or when it is secured to brackets at the rear of the machine. On several types of two-passenger automobiles no provision is made for carrying the extra tires in an upright position, the tire in these cases being laid down and strapped to the rear part of the car. When the tire is carried in the latter manner, my improved receptacle may be laid on its side and secured within the tire in the same manner, or it may be permanently secured to the machine. The body may be made of any suitable material such as trunk board, sheet metal or the like. I preferably use sheet metal as it is more durable. In order to secure the receptacle to the tire, or vice versa, I preferably provide, on the outer periphery thereof, straps which are formed in part with flexible metal and in part with leather. The metal parts 27 of the straps are secured to the body and preferably extend around the tire 25 to a short distance past the center of the tread. Leather strips 28 and 29 are secured to either end of the metal strips 27 and are provided with spring buckles 30. The member 31 of the buckle is secured to the strap 28 and is provided with slots 32 adapted to receive the tongue 33 of the buckle member 34 which is secured to the strap 29. The tongue is pivoted to the member 34 as at 35 and is held in an open or closed position by the lip 36 of the tongue 33 bearing against the spring 37 on the buckle member 34.

The front sheet 37 of the body is provided with an opening 38 that may be of any desirable size or shape though it is preferably circular. The front sheet is formed with an inwardly extending conical-shape flange 39 which extends entirely around the opening. For the purpose of stiffening and strengthening the sheet 37 around the opening the flange 39 may be formed with an inwardly projecting rim 40 although this may be omitted. The sheet is formed near the opening 38 and concentric therewith with an annular raised portion or corrugation 41.

The opening 38 is closed by a door which is adapted to bear upon the front sheet 37 between the corrugation 41 and the edge of the opening and is also formed so as to provide a wedging engagement with the flange 39. The door 42 is preferably made of a dished piece of sheet metal which is hinged to the body by means of a hinge 43 that extends over the corrugation 41 and is secured to the front sheet by means of rivets 44, 45. The door 42 is formed with its edge flattened out as at 46 to take an annular gasket 47, which is preferably made of rubber, though obviously leather or any suitable form of soft material might be used, and is formed with a groove 48. When the gasket is made of an endless circular piece of rubber, as is preferable, it can be stretched enough to slip over the edge of the door. The inner side 49 of the gasket bears against the front sheet 37 as at 50 and the outer periphery of the gasket fits within the inner periphery of the annular corrugation 41. The gasket is also formed on its inner side with a flange 51 which is provided with a taper corresponding to the taper of the flange 39 so as to have a wedging engagement with the flange 39. The corrugation 41 preferably extends outwardly beyond the gasket 47 and therefore acts as a water shed for the door decreasing the likelihood of water seeping into the receptacle through the joint between the gasket and the body. In order to hold the door closed I provide a spring hasp 52 which coöperates with the gasket 47 in a manner to insure a very close fit of the door in its seat which will prevent dust, rain, and the like, from entering the receptacle. The spring hasp 52 is secured to the door 42, extends over the corrugation 41, and is formed with a slot 53 which is adapted to receive a knob 55, the shank 56 of which is reduced as at 57 and is revolvably engaged with a plate 58 secured to the front sheet 37 by means of rivets 59. The hasp is bent and put under tension when it is brought down over the head of the knob. It is held in this position by giving the knob a half turn, the inner edge of the head of the knob seating in a groove 60 in the hasp formed between the ribs 61 and 62. When the hasp is held down in this manner the gasket is held down tightly against the sheet 37 as shown at 50 and the flange 51 of the gasket is held in a wedging engagement with the flange 39. This construction provides a closure for the receptacle which is very secure and tight so as to prevent dust and rain from entering the receptacle which will automatically take up wear and any loosening of the parts and will not gap or open up with the vibration of the automobile.

Means for locking the door is provided by securing an angular piece of metal 63 to the hasp and providing it with a perforation 64

which will register with one or other of the perforations 65 in the latch 55 so as to receive the link 66 of a padlock 67. The body of the receptacle is preferably strengthened by the use of an angular brace 68 held in place by rivets 45, 59, 69, 70 and 71, although in some cases this will not be necessary.

While I have described my invention in its preferred embodiment, I do not wish to limit myself to the particular form shown and described as modifications might be made without departure from my invention.

I claim:

1. A receptacle of the character described, comprising a cylindrical body provided with a circular opening, an inwardly extending conical-shaped flange extending around said opening, a dished sheet metal door for said opening hinged to the body, a circular, endless rubber gasket engaging the edge of said cover plate and provided with a conical-shaped flange, and resilient means for holding the flange on said gasket in wedging engagement with the flange around said opening.

2. In a receptacle of the character described, the combination with a body provided with an opening, an inwardly extending flange around the opening, a door for said opening comprising a metal plate, a gasket provided with a groove adapted to fit tightly over the edge of said plate, a tapered flange on said gasket adapted to be wedged into said opening, a spring hasp secured to said door, and a knob on said body which is engaged by said hasp so as to hold the gasket on said closure in said wedging engagement, said body being formed with a rib concentric with said opening for the purpose described.

3. In a receptacle of the character described the combination with a box having an opening in one side, of a door hinged to the box at one side of said opening, a slotted spring hasp on said door and a revoluble knob on the box adapted to extend through the slot in the hasp, the hasp being formed with a transverse groove in which the knob seats when in locking position.

4. In a receptacle of the character described the combination with a box provided with an opening in one side and formed with an upwardly extending rib and with an inturned flange around said opening, of a door hinged to said box, a gasket engaging the edge of the door and adapted to seat against said rib and flange, and means for locking the door in closed position.

5. In a receptacle of the character described the combination with a box provided with an opening in one side and formed with an outwardly extending rib and an inturned flange around said opening, of a dished sheet metal door, a resilient gasket engaging the edge of the door and adapted to seat

against said rib and flange, a hasp on said door and means on the box for engaging the free end of the hasp to force the door to its closed position.

- 5 6. In a receptacle of the character described, the combination with a box provided with an opening in one side and formed with an inturned conical-shaped flange around said opening, of a dished sheet metal door
10 hinged to the box and provided with a horizontal flange, a gasket provided with a

groove adapted to fit over the edge of said horizontal flange and formed with a conical-shaped flange adapted to seat against said inturned flange when the door is in 15 closed position, and resilient means for locking the door in closed position.

RICHARD EISENMAN.
